(57) **CLAIM**

The ornamental design for a strap rigging for a bucket, as shown and described.

DESCRIPTION

FIG. 1 is a right side elevation view of a strap rigging for a bucket, showing my new design in its environment;

FIG. 2 is a front elevation view thereof;

FIG. 3 is a rear elevation view thereof;

FIG. 4 is a right side elevation view thereof;

FIG. 5 is a left side elevation view thereof;

FIG. 6 is a bottom view thereof;

FIG. 7 is a top plan view thereof; and,

FIG. 8 is an alternate right side elevation view shown in an environment of use.

The broken lines in FIGS. 1 and 8 depict environmental subject matter and form no part of the claimed design.

1 Claim, 5 Drawing Sheets

FIG. 1

FIG. 2
